UNITED STATES PATENT OFFICE.

HARRY GRANVILLE AND FRANK KOCH, OF SCRANTON, PENNSYLVANIA.

STOP MECHANISM FOR MOTION-PICTURE MACHINES.

1,318,203.

Specification of Letters Patent.

Patented Oct. 7, 1919.

Application filed January 13, 1919. Serial No. 270,858.

To all whom it may concern:

Be it known that we, HARRY GRANVILLE and FRANK KOCH, citizens of the United States, residing at Scranton, in the county 5 of Lackawanna and State of Pennsylvania, have invented certain new and useful Improvements in Stop Mechanism for Motion-Picture Machines; and we do hereby declare the following to be a full, clear, and 10 exact description of the invention, such as will enable others skilled in the art to which it appertains to make and use the same.

This invention relates to motion picture apparatus, and more particularly to an 15 automatic stop mechanism therefor.

It is well known that several causes exist 20 for the frequent fires in motion picture machines due to the beam of light being permitted to strike the very inflammable film 25 on which the negatives are formed. Divers means have been proposed for interrupting the light in its passage to the film when the latter becomes motionless at the apertured plate, the object of this being to prevent the film from being ignited by the beam of light. Fires may be caused therefore as the 30 result either of the reel backing up which permits the film to slow down or stop in front of the apertured plates; or if the film 35 breaks and a portion is exposed at the aperture, and again fires will result if the driving belt of the machine breaks and in many of these emergencies and eventualities as a usual thing the machine continues to run.

It is the object of the present invention to 40 provide for the interruption of the operation of the driving motor of the machine upon the occurrence of any of these causes and also of others well known to those versed in 45 the art. A further object of the invention is to provide combined means for interrupting the flow of light to the film and also to secure simultaneously or concurrently the interruption of the operation of the driving 50 motor from any one or possible combinations of the above causes. Among the objects of the invention may be mentioned the providing of a film control device connected to automatically acting means for interrupting 55 the flow of the beam of light and also for interrupting the motion of the machine and further to provide an apparatus for these purposes which is simple in construction and readily applied to existing machines or combined with the organization of

new machines, and which is relatively inexpensive and reliable in operation.

With these and other objects in view as will be rendered manifest to those skilled in the art, the invention consists in the construction, the combination, and in details and arrangement of the parts, as will be more particularly described in the following specification relative to the embodiment of the invention illustrated in the accompanying drawings in which Figure 1 is a side elevation of the apparatus as combined with a swinging door commonly employed to cover guide roller and feed sprockets for the film; and Fig. 2 is a rear elevation of the 60 door with the automatic mechanism thereon.

The present invention may be said to be an improvement in the form of construction of the motion picture apparatus disclosed in Patent No. 1,277,951, dated September 3, 1918. But obviously the novel mechanism controlling the interruption of the operation of the motor may be appropriately controlled by and adapted to other types of motion picture apparatus. In the above identified patent and in the present application A indicates the usual apertured plate through which a beam of light from a suitable source is projected on the film B, which passes around suitable feed sprockets 20 to 75 the lower guide rolls 21 and between which sprocket and rollers is arranged a tension device comprising a set of rollers 16 on a shaft 14 which is secured to a swinging arm 10 and projects laterally therefrom. The 80 arm 10 is pivotally mounted on a stud 12 and is connected to a chain 7 or other suitable flexible element extended rearwardly through or around a guide 8, which together with the pivot 12, is shown as mounted on the 85 usual door D of the apparatus; the upper end of the chain 7 after passing from the guide 8 being connected to a shutter S which is pivoted at 5 and is normally thrust upward in a vertical or light-cutting position 90 by means of a spring 6, shown as coiled around the hinge or pivot 5. From this it will be seen that when the shutter S is pressed to the position shown in Fig. 1 the 95 arm 10 may be swung about its pivot 12 so 100 that the rollers 16 and the shaft 14 therefore stand parallel to the normal position of the film B, passing tangentially down from the feed sprocket 20 and when the 105 film is tensioned it controls movement of the 110

arm 10 and the rollers 16 about the pivot 12 and therefore prevents the automatic cutting-out movement of the shutter S under the impulse of its spring 6.

5 The present improvement contemplates the combination with a motion picture apparatus such as shown for example by the above described type, means for stopping the operation of the driving motor in the 10 event that because of the backing up of a reel, or the breaking of the driving belt, or of the film, the film becomes substantially stationary in front of the light aperture. To that end we have shown as connected to the 15 chain 7 of the automatic device, an arm 25 secured to and insulated from a switch or circuit breaker 26, as at 40, swinging about a pivot screw 27 mounted on a base of insulating material 28 which is secured to the 20 door D. The circuit breaker, or arm 26, is shown as provided with a lug 29 to which is connected a spring 30, one end of which is attached to a fixed support which may be connected as at 31 to a lead 32 of a part of 25 the motor circuit, another lead of which is shown at 33 as connected at 34 to a contact piece 35 with which the swinging switch or arm 26 is adapted to be contacted to close the circuit when the chain 7, to which it is 30 connected, is pulled downwardly by the setting of the film control device including the arm 10.

From the above it will be seen that when 35 the machine is operating in the normal manner and the film is under proper tension the rollers 16 on the shaft 14 are supported on and controlled by the adjacent stretch of the film and the shutter S and the circuit breaking arm 26 are held in set 40 positions against the tendency of the spring 6 and the spring 30 to automatically actuate their respective parts. In the event that the film B gives way under the pressure of the rollers 16 produced by the springs 6 and 45 30 then the shutter will be allowed to swing to the light-cutting off position and the circuit breaker will be thrown open by its spring 30 and the motor circuit broken so that the motor will cease to operate and the 50 machine become motionless.

It is to be understood that various modifications and alterations and changes in form

and construction may be resorted to in the construction of an apparatus within the spirit of the invention and scope of the appended claims.

We claim:

1. In a motion picture apparatus, a housing including a gate, an insulator base thereon, a motor circuit, a lever pivotally supported by said base, a tension spring connected to one terminal of said motor circuit and secured to one end of said lever, a contact member forming a second terminal for said circuit, a horizontally swinging tension device for the film, and means connecting said tension device and the other end of said lever whereby said lever is brought into engagement with the contact member.

2. In a motion picture apparatus, a housing including a gate, an insulator base mounted thereon, a motor circuit having a pair of unconnected terminals, a horizontally pivoted bell crank lever supported thereby, a tension device secured to one arm thereof, and connected to a terminal of said motor circuit, a contact member secured to another of said terminals, a horizontally swinging tension device for the film vertically pivoted to said gate, an extension secured to and insulated from the other arm of said bell crank, and means connecting said extension and said tension device, whereby the last named arm of said bell crank is brought into engagement with the contact member when the tension device is brought into engagement with the film.

3. In a motion picture machine having a motor and an open circuit therefor, a tension spring having one end connected to one terminal of said circuit and a contact member secured to a second terminal thereof, a bell crank lever pivoted intermediate the terminals and having the other end of said spring secured to one arm thereof, a film tension device connected to the other arm of said bell crank, and means connecting said last named arm and said tension device whereby said arm is brought into engagement with said contact.

In testimony whereof we affix our signatures.

HARRY GRANVILLE.
FRANK KOCH.
